No 1260

Fig. 2.

Samuel Morgan
Design for a fire shovel.
Patented June 19 1860.

Fig. 1.

Improved Pattern, or Design
By Samuel Morgan of Somerville, Mass.

Fig. 2. Large   Fig. 1. Small

Dec. 1260

Samuel Morgan, of South Norwalk, Conn.
Assignor to

S. Morgan and C. Adams, of N. York.
Letters Patent No. 1260, dated June 19, 1860.

The schedule referred to in these Letters Patent, and making part of the same.

To all to whom it may concern:

Be it known that I, Samuel Morgan, of South Norwalk, County of Fairfield, and State of Connecticut, have invented or produced a new and original design for a fire Shovel, and I do hereby declare that the following is a full and exact description of the same, referring to the drawings or illustrations in which the same letters indicate like parts in each of the figures.

In the accompanying drawings or Photographic Views, are shown a new and original design for a cast metal fire Shovel.

Fig. 1. is a partial top and side view, showing the shape and configuration thereof.

Fig. 2. is a partial bottom and side view, showing also its shape and configuration.

a. is a flat bottom - b. is an angular flat, side, configuration upon the rounded end and sides of the bottom a. - c. is a concave handle having a strengthening bead d. configuration upon or around the edges thereof.

The whole combined to produce a plain and rich design for a fire Shovel.

What I claim therefore and desire to secure by Letters Patent, is the design for a cast metal fire Shovel, as herein above illustrated and described.

In witness whereof, I have hereunto set my hand and seal this 10th day of May 1860.

Witnesses.
